UNITED STATES PATENT OFFICE

2,520,804

WATERCRAFT WITH PIVOTED FLAPPERS

Oliver A. Hollar, Hanford, Calif.

Application December 24, 1947, Serial No. 793,690

1 Claim. (Cl. 115—4)

1

The present invention relates to new and useful improvements in water craft for supporting a single person and more particularly to means for propelling the water craft by a rocking movement thereof.

An important object of the invention is to provide a readily rockable water craft having pivoted paddles or flappers at each side thereof arranged to cause a forward propelling movement of the water craft when the same is rocked from side to side by the occupant.

Another object of the invention is to provide a water craft for supporting a person in a standing position thereon to effectively cause a propelling movement thereof and to also provide means for steering the water craft.

A still further object is to provide a device of this character of simple and practical construction, which is efficient and reliable in operation, relatively inexpensive to manufacture and otherwise well adapted for the purposes for which the same is intended.

the same is intended.

Other objects and advantages reside in the details of construction and operation as more fully hereinafter described and claimed, reference being had to the accompanying drawings forming part hereof, wherein like numerals refer to like parts throughout, and in which:

like parts throughout, and in which:
Figure 1 is top plan view,
Figure 2 is a side elevational view,
Figure 3 is a front elevational view,

Figure 4 is an enlarged transverse sectional view of one of the propelling flappers. Figure 5 is an enlarged fragmentary vertical sectional view of the steering post taken sub-

Figure 6 is an enlarged vertical sectional view of one of the flapper supports taken substantially on the line 5—5 of Figure 3, and

Referring now to the drawings in detail wherein for the purpose of illustration I have disclosed a preferred embodiment of the invention the numeral 5 designates the central main pontoon or float for the boat or water craft on which is supported front and rear upright frames 6 and 7 extending outwardly at opposite sides of the central pontoon and having a platform 8 supported on the top of the frames.

The sides of the frames 6 and 7 are provided with brackets 9 on which relatively small balancing pontoons or outriggers 10 are supported, the balancing pontoons being positioned outwardly at each side of the central pontoon 5 and parallel thereto. The axis of the pontoons 5 and 10 are coplanar to normally support the platform 8 in

a horizontal position above the surface of the water.

5 A plate 11 is secured in an upright position at the lower side edges of the front and rear frames 6 and 7 and from which a pin 12 projects outwardly in a slightly downwardly inclined position. A substantially flat hollow flapper 13 of substantially air-foil construction is provided with a bearing or bushing 14 extending transversely thereof and pivotally supported on the pin 12. The flapper is secured in position on the pin by a nut 15 threaded on the outer end thereof to provide a vertical swinging movement 10 of the flapper. The flapper is pivoted slightly forwardly of its center to provide a relatively 15 longer trailing edge 16.

Upper and lower stop pins 17 and 18 project outwardly from the plate 11 between which the trailing edge 16 of the flapper is vertically swingable, the stops limiting the upward and downward swinging movement of the flapper. A hollow steering post 19 is suitably supported in an upright position at a front edge of the platform 8 and in which a steering shaft 20 is rotatably supported with a handle 21 at its upper end and oppositely extending arms 22 at its lower end and to which the front ends of cords or steering cables 23 are attached. The rear ends of the cables are attached to steering arms 24 extending oppositely at the upper end of a rudder post 25 journaled in a supporting bracket 26 extending rearwardly from the central pontoon 5. The rudder post 25 carries a rudder 27.

Rudder post 25 carries a rudder 21. In the operation of the device a person is supported in a standing position on the platform 8 to impart a rocking movement to the boat whereby to raise and lower the flappers 13 in the water. The flappers being pivoted forwardly of their centers and the pivotal movement of the flappers being limited by the upper and lower stops 17 and 18 will result in relatively short strokes of the flappers to change from an upwardly to a downwardly inclined position by an opposite tilting movement of the platform. The initial upward or downward movement of one side of the platform will quickly swing the rear end of the flappers at that side upwardly or downwardly into an inclined position and are held in that position by the stops, and the continued movement of that side of the platform in the same direction will maintain the flappers in the inclined position, such as shown in Figure 4, and will tend to force the water under the flappers rearwardly and thus move the device forwardly. This action will occur when the flap-

pers are inclined upwardly as well as downwardly.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A water craft comprising a main central pontoon, a frame supported thereon, a platform supported on the frame, outrigger pontoons at each side of the central pontoon and carried by the frame, said frame including a lower frame structure positioned outwardly at opposite sides of the central pontoon and below the center thereof to support said lower frame structure submerged, horizontal pins projecting outwardly at each side of the lower frame structure, rigid flappers of airfoil construction rockably supported forwardly

of their centers on said pins for vertical swinging movement of the trailing edges of the flappers to propel the water craft by rocking movement of the platform, and stop pins carried by the lower frame structure above and below the trailing edges of the flappers to limit swinging movement thereof.
